UNITED STATES PATENT OFFICE.

BIRGER LJUNGSTRÖM, OF STOCKHOLM, SWEDEN, ASSIGNOR TO AKTIEBOLAGET LJUNGSTRÖMS ANGTURBIN, OF FINSPÅNG, SWEDEN.

COMMUTATOR PROVIDED WITH SEGMENTS OR BARS AND SLIP-RINGS.

1,102,525.

Specification of Letters Patent. Patented July 7, 1914.

Application filed January 24, 1914. Serial No. 814,140.

To all whom it may concern:

Be it known that I, BIRGER LJUNGSTRÖM, a subject of the King of Sweden, and a citizen of Sweden, residing at No. 52 Regeringsgatan, Stockholm, in the Kingdom of Sweden, have invented certain new and useful Improvements in Commutators Provided with Segments or Bars and Slip-Rings, of which the following is a specification.

This invention relates to an improvement in commutators provided with segments and rings and has for its objects to secure more effective contact, to lessen the production of heat, to reduce friction and to cheapen the cost of construction.

To these ends the said invention consists in the construction and combination of parts hereinafter more particularly set forth and claimed.

In the accompanying drawings Figure 1 represents a side elevation of a commutator embodying my invention, partly in longitudinal vertical section; Fig. 2 represents a detail vertical section enlarged of a part of one of the additional commutators; Fig. 3 represents a diagrammatic view enlarged, of one of the conductors electrically connecting one of the additional commutators to the main commutator, showing also certain proximate parts.

The commutator shaft *i* is enlarged to form a certain number of external bars or segments *f*, which connect electrically with conductors *t* leading to two additional commutators, of less diameter than the main commutator and arranged one on each side of the latter, said conductors being bent as shown in Fig. 1 to form in effect continuous bars having the same function for the lesser commutators as the bars or segments *f* have for the main commutators. Rings *e*,

surrounding the bars thus formed on the additional commutators, are of course smaller than would be possible if applied to the main commutator. They form two sets, one being on each additional commutator.

The reduced diameter of the rings and the circular series of bars which they surround on the lesser commutators, does not require any reduction of the main commutator, but lessens friction and heat owing to the diminished peripheral velocity and leverage and is found also to possess other advantages first above named. It is not necessary that more than one additional commutator should be employed.

Having thus described my invention what I claim as new and desire to secure by Letters Patent is:

1. A commutator provided with a series of external segments or bars, in combination with an additional commutator of less diameter similarly provided with bars electrically connected to the bars first mentioned and rings which fit on the bars of the lesser commutator and are electrically connected thereto.

2. A commutator provided with a series of external segments of bars in combination with an additional commutator of less diameter also provided with external bars and with rings surrounding the same and electrically connected thereto, the latter bars being connected by integral conductors with the bars or segments of the main commutator.

In testimony whereof I have affixed my signature in presence of two witnesses.

BIRGER LJUNGSTRÖM.
